DESIGN FOR A PINAFORE DRESS

Arthur Esch, New York, N. Y.

Application April 30, 1942, Serial No. 106,761

Term of patent 3½ years

To all whom it may concern:

Be it known that I, Arthur Esch, a citizen of the United States, residing at New York, in the county of New York and State of New York, have invented a new, original, and ornamental Design for a Pinafore Dress, of which the following is a specification, reference being had to the accompanying drawing, forming a part thereof.

In the drawing:

Fig. 1 is a front elevational view of a pinafore dress, showing my new design; and

Fig. 2 is a rear elevational view thereof.

I claim:

The ornamental design for a pinafore dress, as shown.

ARTHUR ESCH.
